STAMPING MECHANISM.

1,426,000.

Specification of Letters Patent. Patented Aug. 15, 1922.

Application filed November 11, 1919. Serial No. 337,202.

To all whom it may concern:

Be it known that I, ELOF NORDSTROM, a citizen of the United States, and residing at Newark, county of Essex, and State of New Jersey, have invented certain new and useful Improvements in Stamping Mechanism, of which the following is a full and clear specification.

This invention relates to stamping mechanism and more especially to that type of stamping mechanism in which blank stamping and shaping dies are arranged in suitable relation to each other to have the blank which is cut in one die, stamped directly into the other die. The object of this invention is to provide improved stamping mechanism of this character whereby the space between the blank cutting plunger and the shaping die is positively controlled so that sufficient allowance is made for permitting the metal to be drawn into the shaping stamp and die. One of the objects of the present invention is to provide suitable spacing means for the stamping mechanism shown and described in Patent No. 1,212,665 which was granted in my name on January 16th, 1917. In the drawings which show the preferred embodiment of my invention, Figure 1 is a side elevation of the stamping mechanism constructed in accordance with the principles of the present invention, parts being broken away and parts shown in section;

Figure 2 is a top plan view of the same, parts being shown in section;

Figure 3 is a section on the line 3—3, Figure 1, parts being shown in elevation.

Fig. 4 is a view in direction of arrow of the section 4—4 in Fig. 1.

According to the embodiment of my invention shown on the drawings, a suitable base or support 1 which may be a heavy member of the main frame of a machine to which the invention may be applied, serves to mount an upright or bracket 2 which is provided with an offset portion 3 in the form of a column or tubular support. This column is provided above with an enlargement or thickened portion 4 which is surmounted by a cap plate 5 which constitutes a blank cutting die. Reciprocably mounted in the column 3 is a hollow blank cutting plunger 6 which is provided at its

lower end with a threaded portion 7 on 55 which is adjustably mounted a spool 8, said spool being provided with a peripheral groove 9 for receiving the inwardly presented pins 10 which are mounted in the bifurcated end of a lever arm 11, the hub 12 of said lever arm being pivotally mounted on a pin 13 which is carried by the upright or bracket 2. The hub 12 is provided with offset lever arm 14 which is pivotally connected by a pin 15 with a yoke 16 within 65 which is reciprocably mounted the lower end of a connecting rod 17. The lower end of said rod 17 has keyed thereto a collar 18 which limits the upward displacement of rod 17 with respect to the yoke 16. Interposed between the yoke 16 and an adjustable abutment 19 on the upper end of the rod 17 is a compression spring 20 which normally tends to displace the rod 17 upwardly. The upper end of the rod 17 is pivotally 70 connected at 21 with one arm of a bent lever 22 which is pivoted at 23, the other arm 23 of said lever being provided with a cam roller 24 which operates in a cam groove 25. As shown in Figure 3, a space 26 is provided around the upper end of blank cutting plunger 6, a pair of stock feeding elements 27 being provided for moving the blank forming material across the under-surface of the blank cutting die 5 at times 75 when the plunger 6 is in lowered position. Reciprocably mounted within the blank cutting plunger 6 is a forming plunger 28 which cooperates at its upper end with a die 29 provided in a suitable plate or table 30. The 80 threaded lower end of plunger 28 carries a spool 31 provided with a peripheral groove 32 which receives the inwardly presented pins 33 carried by the bifurcated end of a lever arm 34. Said lever arm 34 is carried 85 by a hub 35 which also carries an offset lever arm 36. The lever 34, 35, 36 is fulcrummed on a pin 37. A pin 38 serves to pivotally connect the lever arm 36 with the lowered end 39 of a connecting rod, the upper end of said connecting rod being pivotally connected to a lever arm 40 of a bell crank lever which is fulcrummed on a pin 41 and provided with a cam arm 42 which carries a cam roller 43 cooperating with a 90 cam slot 44. The cam slots 25 and 44 are formed in the periphery of a cam 45 which is keyed to a cam shaft 46. A check nut 95

100

105

47 on the lower end of plunger 28 serves to retain the spool 31 in adjusted position. A similar check nut 48 on the hollow plunger 36 serves a similar purpose for the spool 8.

5 After each blank cutting operation, it is essential to have a suitable space provided between the upper end of blank cutting plunger 6 and the undersurface of the plate or table 30 which carries the forming die 10 29. Suitable means for effecting this result so as to permit the metal in the blank to draw freely as the forming plunger 28 forces it upwardly into the die 29, are provided as follows.

15 Reciprocably mounted in the enlargement 4 of the collar 3, is a spacing rod or strut 49 which has its lower end carried by the lock nut 48. By means of this construction, a positive abutment is secured for exactly pre- 20 determining the space relationship between the blank cutting plunger and metal drawing die for different thicknesses of metal. By means of the spring 20 on the connecting rod 17, the blank cutting operation is relieved 25 from undesirable stresses resulting from having the rod 49 of positive length interposed between the plate or table 30 and the lock nut 48.

Briefly described, the operation of my im- 30 proved stamping mechanism is as follows: As the cam block 45 rotates from the position shown in Fig. 1, plungers 6 and 28 are returned downwardly from their position shown in Fig. 3. Immediately the stock or 35 tape out of which the caps are constructed is fed from the right according to Fig. 1 through a passageway which extends under the cap plate 5 which is provided with the blank cutting die. This movement is pro- 40 duced by the reciprocating elements 27 which alternately engage and release the stock as shown and described in Patent No. 1,212,665 to Nordstrom dated January 16th, 1917. After a forward movement of the 45 tape, the blank cutting plunger 6 is moved upwardly by the cam roller 24 moving toward the left in cam groove 25. Near the end of the blank cutting movement the metal drawing plunger 28 begins an upward move- 50 ment as the cam roller 43 is moved toward the left by cam groove 44. The upward movement of the blank cutting plunger is positively limited in its approach to the die plate 30 by means of the spacing rod 49 55 which constitutes a rigid abutment interposed between the die plate 30 and the lock nut 48 on plunger 6. A rigid block or projection 50 is disposed in the line of thrust of the rod 49 to support the die plate 30 at 60 the times it is subject to the thrust of rod 49 under the pressure of spring 20 on connecting rod 17.

I claim:

1. In a machine of the character described, 65 the combination with blank punching mech-

anism and blank shaping mechanism, said mechanisms including spaced die plates and plungers cooperating respectively with said die plates, of means constituting an abutment for limiting the approach of the blank 70 cutting plunger with respect to the blank shaping die plate.

2. In a machine of the character described, a blank-shaping die, a blank-shaping plunger, a blank-cutting die, a blank-cutting 75 plunger cooperating with said blank-cutting die for cutting a blank to be shaped in said blank-shaping die and cooperating with said blank-shaping die for providing a drawing gap for the blank during the shaping operation, means yieldably driving said blank-cutting plunger to its work, and rigid means interposed between said blank-shaping die and a part which partakes of the movement 80 of said blank-cutting plunger for positively defining the size of said blank-drawing gap.

3. In a machine of the character described, a blank cutting die plate, a forming die plate coaxially spaced therefrom, a hollow blank cutting plunger between which and the cutting die plate there is relative movement, a plunger within said blank cutting plunger cooperating with said forming die plate, and a strut interposed between said forming die plate and a part carried by said blank cutting plunger, said strut determining the least space between said blank cutting plunger and said forming die.

4. In a machine of the character described, coaxial blank cutting and forming dies, 100 concentrically mounted plungers cooperating respectively with said dies, and a spacing rod mounted on the blank cutting plunger and adapted to abut against the forming die for positively limiting the drawing space for 105 the blank during the forming operation.

5. In a machine of the character described, coaxially arranged blank cutting and metal drawing dies and plungers, levers for reciprocating said plungers, an adjustable connection between the blank cutting plunger and the lever to which it is connected, said connection including a lock nut, and a spacing rod carried by said lock nut and adapted to abut against the metal drawing die for 110 limiting the approach of said blank cutting plunger thereto.

6. In a machine of the character described, coaxially arranged blank cutting and metal drawing dies and plungers, levers for reciprocating said plungers, an adjustable connection between the blank cutting plunger and the lever to which it is connected, said connection including a lock nut, a spacing rod carried by said lock nut and adapted to 115 abut against the metal drawing die for limiting the approach of said blank cutting plunger thereto and yieldable means for oscillating the last mentioned lever.

7. In a machine of the character described, 120

coaxially arranged blank cutting and metal drawing dies and plungers, levers for reciprocating said plungers, an adjustable connection between the blank cutting plunger and the lever to which it is connected, said connection including a lock nut, a spacing rod carried by said lock nut and adapted to

abut against the metal drawing die for limiting the approach of said blank cutting plunger thereto and means for reinforcing the drawing die to resist the thrust of said spacing rod.

ELOF NORDSTROM.
